UNITED STATES PATENT OFFICE.

JOSEPH A. COSTELLO, OF CLEVELAND, OHIO.

ART OF MAKING HEXAGONAL HOT-METAL PIECES FOR MAKING HEXAGONAL NUT BLANKS.

1,405,969.

Specification of Letters Patent.

Patented Feb. 7, 1922.

Application filed March 27, 1920. Serial No. 369,423.

To all whom it may concern:

Be it known that I, JOSEPH A. COSTELLO, a citizen of the United States, and residing at Cleveland, in the county of Cuyahoga and State of Ohio, have invented a new and useful Improvement in the Art of Making Hexagonal Hot-Metal Pieces for Making Hexagonal Nut Blanks, of which the following is a specification.

10 This invention relates to an improvement in the art of making hexagonal hot metal pieces for making hexagonal nut-blanks, and pertains more especially to the subjection of a hot metal bar to such forging operations 15 as will produce improved hexagonal hot metal pieces which have the configuration and characteristics required to render them more especially suitable for subjecting them to operations such, for instance, as are involved in the nut-blank-making process set forth in the specification of United States 20 Letters Patent, No. 1,287,644, granted to me Dec. 17, 1918.

One object of the present invention is to 25 have the configuration and characteristics of the hexagonal hot metal piece, which is to be subjected to said patented process, such as to reduce the wear on the tools or devices or apparatus employed in practising said 30 process, and furthermore such as to facilitate the spreading and distribution of metal during the displacement of metal in practising said process and thereby materially assist in the formation of sharp corners on 35 the resulting hexagonal nut-blank.

Another object is still further to reduce the cost of production in the manufacture of forged hexagonal nut-blanks.

Another object is to economically produce 40 my improved hexagonal hot metal piece by forging operations on a hot metal bar which is rectangular in cross-section and which, although having a width which measures more than said hot piece measures between 45 diametrically opposite sides of the piece, preferably has a thickness which measures less than the mean thickness of said piece.

With these objects in view, and to attain any other object hereinafter appearing, this 50 invention consists in the steps or process hereinafter described in this specification and pointed out in the claims.

Apparatus suitable for use in carrying out my invention is illustrated in the accom-

panying drawings in which Figure 1 is a 55 side elevation of portions of two opposite forging tools having wedge-shaped members arranged to enter a hot metal bar shown in position to be entered at its longitudinal edges by said wedge-shaped members. Fig. 60 2 is a cross-section of said bar at the line 2—2, Fig. 1. Fig. 3 is a side elevation showing the bar entered by the wedge-shaped members of the forging tools. Fig. 4 is a vertical section taken along the line 4—4, 65 Fig. 3, looking in the direction indicated by the arrows. Fig. 5 is a side elevation showing the aforesaid wedge-shaped members withdrawn from the bar after the operation illustrated in Fig. 4. Fig. 6 is a side 70 elevation showing the bar fed forwardly endwise from the position shown in Fig. 5 into position to be again entered by the aforesaid wedge-shaped members. Fig. 7 is a side elevation showing the bar in the 75 position shown in Fig. 6 and again entered by said wedge-shaped members. Fig. 8 is a side view of a hexagonal hot piece produced by my improved process, and Fig. 9 is a side view in central section of said piece. 80

Referring to said drawings, 10 indicates a hot metal bar which is to be operated on by my improved process to form improved hexagonal hot metal pieces which have the configuration and characteristics required to 85 render them more especially suitable to be operated on by apparatus such, for instance, as shown and described in the specification of the hereinbefore enumerated Letters Patent. Said bar is preferably rectangular in cross section, as shown in Fig. 2. Said bar is adapted to be intermittently fed horizontally and on edge endwise in one direction. Means for supporting a hot metal bar while it is being fed endwise are too well 90 known to require illustration and description in this specification. Suffice it to state that the bar is supported and fed in any approved manner.

Two oppositely and substantially vertically arranged forging tools, each of which terminates in a wedge-shaped member 12, are shown in Fig. 1 as relatively spaced the distance required to permit the feeding of the hot bar 10 endwise between the said 100 forging tools. In Fig. 1 the wedge-shaped member of each forging tool is substantially 105 at a right angle to said bar and at its thin

end has an edge 13 extending transversely of the adjacent longitudinal edge of the bar and long enough not only to extend transversely of said edge of the bar but somewhat beyond the sides of the bar as shown in Fig. 4. The wedge-shaped member 12 of each forging tool has its converging surfaces 14 and 15 facing toward the bar 10 and rearwardly and forwardly respectively 10 in relation to the path of the bar and sloping substantially correspondingly toward each other in the direction of and terminating in the edge 13 of the wedge, and said sloping surfaces are substantially at an angle of sixty degrees to said path. Preferably the hot bar 10 has a thickness which measures less than the mean thickness of the hexagonal pieces into which the bar is to be converted, and said bar has a width 20 which measures more than the diameter between diametrically opposite sides of said hexagonal pieces. For the production of hexagonal hot metal pieces which are suitable for making hexagonal nut-blanks which 25 are substantially three-fourths of an inch thick and have a diameter of substantially one and one-fourth inches between diametrically opposite sides I preferably produce a hot metal bar which is rectangular in cross-section and measures substantially five-eighths of an inch in thickness and substantially one and one-half inches in width, and said bar is fed substantially horizontally and on edge between the wedge-shaped 30 members 12 into a position in which the forward end portion of the bar extends between said wedge-shaped members at a predetermined point where the bar has substantially its full original width, as shown 35 in Fig. 1. It will be observed that the bar illustrated in Fig. 1 has already been operated on and that therefore a portion 16 of said bar extends forwardly beyond said point and is in the form of a partially 40 formed hexagonal piece. Upon feeding the hot bar forwardly endwise to and between the wedge-shaped members 12 the distance required to bring a point on said bar, where the bar has substantially its full original 45 width, in line vertically between said wedge-shaped members, the forging tools comprising said wedge-shaped members are operated, while the bar is at rest, in such a manner that said wedge-shaped members simultaneously enter the bar at opposite longitudinal edges respectively of the bar and substantially at a right angle to the bar and far enough to effect the formation of two 50 opposite V-shaped recesses 17 which, as 55 shown in Fig. 3, extend inwardly from opposite longitudinal edges respectively of the bar and into close proximity to each other and laterally through the bar. It will be 60 observed therefore that said recesses have 65 the walls 18 thereof, which face in the di-

rection of the forward extremity of the bar, forming two adjacent sides of a hexagonal piece shown being formed at 20, Fig. 3, while the hot bar is at rest, and have their rearwardly facing walls 21 forming two adjacent sides of a hexagonal piece which is shown as partially formed at 16, Fig. 1, and as substantially completed at 22, Fig. 3, by the formation of said recesses, and that said walls 18 and 21 are substantially at an angle of sixty degrees to the path of the bar. The substantially completed hexagonal piece shown at 22, Fig. 3, is immediately, upon having been formed, removed from the bar into a die such, for instance, as shown and described in the specification of the herein-before enumerated Letters Patent and operated on in said die as set forth in said specification. I would here remark that the hot bar while at rest is not confined endwise, so as to permit stretching of the bar at any point endwise of the bar, and so that during the formation of recesses in the bar by forging operations such, for instance, as the forming of the recesses 17 by causing the wedge-shaped members 12 to be driven into the bar, the metal between the forming recesses is stretched endwise of the bar. 70 75 80 85 90 95 100 105 110 115 120 125 130 Each forging tool is provided, at the rearwardly facing sloping surface 14 of its wedge-shaped member 12, with a sloping shoulder 23 which extends rearwardly from said surface 14 at a point spaced from the edge 13 of said wedge-shaped member and faces the adjacent longitudinal edge of the bar 10 and extends transversely of said edge and beyond the sides of the bar. The dimensions of the shoulders 23 of the forging tools longitudinally of the hot bar, their contour, and their relation to the path of said bar are such that when the wedge-shaped members 12 of said tools have entered the bar approximately to but not beyond a point central between the longitudinal edges of the bar, as shown in Fig. 3, said shoulders shall have exerted such pressure against said edges from the recesses 17 rearwardly a distance substantially equal to the distance between adjacent corners of the hexagonal piece being formed at 20, Fig. 3, as to displace metal laterally of the bar and thicken the bar adjacent and along said shoulders and as to cause the width of the bar to be reduced from the rear ends of the shoulder-engaged portions of the longitudinal edges of the bar to the recesses 17 and decrease gradually toward said recesses and measure next rearward of said recesses substantially the same as the diameter of said hexagonal piece between diametrically opposite sides of said piece. The shoulders 23 therefore have such arrangement in relation to the edges 13 of the wedge-shaped members 12 of the forging tools that, upon the completion of the operation of said wedge-shaped members on the

hot bar, the distance between the inner end of the shoulder on one forging tool and the inner end of the shoulder on the other forging tool shall measure substantially the 5 same as the diameter between diametrically opposite sides of the hexagonal piece being formed.

When the hot bar has been operated on by the wedge-shaped members 12 to form two 10 adjacent sides 18 of the hexagonal piece shown being formed at 20, Fig. 3, and said bar has been reduced in width adjacent said sides by the operation of the shoulders 23 the forging tools comprising said wedge-shaped members are separated far enough, 15 as shown in Fig. 5 to permit forward endwise movement of the bar, and then the hot bar is fed forwardly endwise, as shown in Fig. 6, a distance substantially equal to one 20 and one-half times the distance between adjacent corners of said hexagonal piece, whereupon said wedge-shaped members are again caused to be driven simultaneously into the hot bar to effect the formation in 25 the bar of two V-shaped recesses 25 which are substantially the same as the recesses 17 hereinbefore described. The formation of the recesses 25 is shown in Fig. 7, and during the operation of the wedge-shaped members 12 to form said recesses metal is so displaced next forward of said wedge-shaped members at the longitudinal edges of the bar that said edges shall have their portions 26, which (see Fig. 6) extend forwardly and inwardly from the point at 30 which said recesses are begun to be formed, rendered substantially parallel and spaced apart a distance which measures substantially the same as the diameter between diametrically opposite sides of the resulting 35 hexagonal product shown at 27, Fig. 7. It will be observed therefore that the second entrance, shown in Fig. 7, of the wedge-shaped members 12 into the hot bar during 40 the formation of a hexagonal piece results in the completion, by the sloping surfaces 15 of said wedge-shaped members, of the formation of the diametrically opposite sides 28 (see Fig. 7) of said hexagonal piece 45 which were begun to be formed by the shoulders 23 during the first entrance of said wedge-shaped members into the bar so far as concerns the formation of said hexagonal piece, and also results in the formation of the 50 remaining two sides 29 of said hexagonal piece. (See Fig. 7.) Said second entrance of the wedge-shaped members 12 into the hot bar to complete the formation of the hexagonal piece being formed is the first 55 entrance of said wedge-shaped members into said bar for the formation of two adjacent sides 30 of the hexagonal piece next to be formed, as shown in Fig. 7. Obviously when the hot bar has been operated on for forming a hexagonal piece already largely formed, 60

as at 16, Fig. 1, preparatory to the first entrance of the wedge-shaped members 12 into said bar for the formation of the next hexagonal piece to be formed, said first entrance of the said wedge-shaped members in to said 70 bar so far as concerns the production of said next hexagonal piece to be formed is the second entrance of the said wedge-shaped members into said bar so far as the completion of the partially formed hexagonal 75 piece shown at 16, Fig. 1, is concerned.

A hexagonal piece formed as hereinbefore described and illustrated as substantially completed at 27, Fig. 7, is immediately upon its formation fed in any approved manner 80 into a die, such, for instance, as shown and described in the specification of the hereinbefore enumerated Letters Patent and operated on in said die by apparatus such, for instance, as shown and described in said 85 specification.

A hexagonal piece produced in accordance with my present invention and illustrated in Figs. 8 and 9, has a mean thickness greater than the thickness of the hot bar from which 90 it was produced and has such configuration and dimensions as to successfully contribute to the attainment of the hereinbefore stated objects. 95

What I claim is—

1. In the art of making hexagonal hot metal pieces for making hexagonal nut-blanks, subjecting an endwise movable hot metal bar to forging operations at a predetermined point in relation to the path 100 of the bar and while the bar is at rest and thereby forming two opposite V-shaped recesses which extend inwardly from opposite longitudinal edges respectively of and laterally through the bar and have the walls 105 thereof which face endwise of the bar in one direction forming two adjacent sides of a hexagonal piece to be produced and have their walls which face in the opposite direction forming two adjacent sides of a 110 hexagonal piece substantially completed by forming said recesses, and during the formation of said recesses exerting such pressure against said edges from said recesses a suitable distance in the last-mentioned direction as to thicken the bar and cause the bar to have its width between the pressure-receiving portions of said edges reduced in the direction of said recesses, then feeding the bar endwise in the first-mentioned direction a predetermined distance, and then again subjecting the bar to forging operations at the aforesaid point and thereby substantially completing the product comprising the aforesaid portions of said edges. 115

2. In the art of making hexagonal hot metal pieces for making hexagonal nut-blanks, producing a hot metal bar adapted to be fed intermittently endwise in one direction and having a width measuring more 120

than the diameter of said pieces between their diametrically opposite sides, subjecting said bar at a predetermined point in relation to its path and while at rest to forging operations and thereby forming two opposite V-shaped recesses which extend inwardly from opposite longitudinal edges respectively of and laterally through the bar and have the walls thereof which face in the direction of the forward extremity of the bar forming two adjacent sides of a hexagonal piece being formed and during the formation of said recesses stretching the metal between them endwise of the bar and exerting pressure against said edges from said recesses rearwardly a distance substantially equal to the distance between adjacent corners of said hexagonal piece, then feeding the bar forwardly endwise a predetermined distance, and then forming like recesses in the bar at the aforesaid point and thereby substantially completing said hexagonal piece.

3. In the art of making hexagonal hot metal pieces for making hexagonal nut-blanks, producing a hot metal bar adapted to be fed intermittently endwise in one direction and having a width measuring more than the diameter of said pieces between their diametrically opposite sides, subjecting said bar at a predetermined point in relation to its path and while at rest to forging operations and thereby forming two opposite V-shaped recesses which extend inwardly from opposite longitudinal edges respectively of and laterally through the bar and have their forwardly facing walls forming two adjacent sides of a hexagonal piece being formed, and during the formation of said recesses stretching the metal between them endwise of the bar and exerting such pressure against said edges from said recesses rearwardly a suitable distance that metal is displaced laterally of the bar and that the width of the bar is reduced from the rear end of the last-mentioned distance to said recesses and caused to measure next rearward of said recesses substantially the same as the aforesaid diameter, then feeding the bar forwardly endwise a predetermined distance, and then forming like recesses in the bar at the aforesaid point.

4. In the art of making hexagonal hot metal pieces for making hexagonal nut-blanks, producing a hot metal bar adapted to be fed intermittently endwise in one direction and having a width measuring more than the diameter of said pieces between their diametrically opposite sides, subjecting said bar at a predetermined point in relation to its path and while at rest to forging operations and thereby forming two opposite V-shaped recesses which extend inwardly from opposite longitudinal edges re-

spectively of and laterally through the bar and have their forwardly facing walls forming two adjacent sides of a hexagonal piece being formed, and while forming said recesses stretching the metal between them endwise of the bar and exerting such pressure against said edges from said recesses rearwardly a suitable distance that the width of the bar gradually decreases from the rear end of the last-mentioned distance toward said recesses and is reduced to such an extent as to measure next rearward of said recesses substantially the same as the aforesaid diameter, then feeding the bar forwardly endwise a predetermined distance, and then forming like recesses in the bar at the aforesaid point and during the formation of the last-mentioned recesses so displacing metal as to render the edges substantially parallel where they extend forwardly from said last-mentioned recesses.

5. In the art of making hexagonal hot metal pieces for making hexagonal nut-blanks, producing a hot metal bar adapted to be fed intermittently endwise in one direction and having a width measuring more than the diameter of said hexagonal pieces between their diametrically opposite sides, subjecting said bar at a predetermined point in relation to its path and while at rest to forging operations and thereby forming two opposite V-shaped recesses which extend inwardly from opposite longitudinal edges respectively of and laterally through the bar and have their forwardly facing walls forming two adjacent sides of a hexagonal piece being formed and while forming said recesses stretching the metal between them endwise of the bar and exerting such pressure against said edges from said recesses rearwardly a distance substantially equal to the distance between adjacent corners of said hexagonal piece that the width of the bar is reduced to such an extent as to measure next rearward of said recesses substantially the same as the aforesaid diameter, then feeding the bar forwardly endwise a distance substantially equal to one and one-half times the distance between the aforesaid corners, and then forming like recesses in the bar at the aforesaid point and thereby substantially completing the aforesaid hexagonal piece.

6. In the art of making hexagonal hot metal pieces for making hexagonal nut-blanks, feeding a hot metal bar which is rectangular in cross-section endwise in one direction and on edge to and between two directly opposite wedge-shaped forging members which are disposed with the transverse edges of their thin ends arranged transversely of the path of the bar, then effecting the entrance of said wedge-shaped members simultaneously into the bar and

thereby forming two adjacent sides of a hexagonal piece to be formed and during the operation of said wedge-shaped members beginning the formation of the remainder of 5 said hexagonal piece, then separating said wedge-shaped members far enough to permit forward endwise movement of the bar between said wedge-shaped members, then feeding said bar forwardly endwise a distance substantially equal to one and one-half times the distance between adjacent corners of said hexagonal piece, and then again effecting the entrance of said wedge-shaped members simultaneously into the bar and 10 thereby substantially completing the formation of said hexagonal piece.

7. In the art of making hexagonal hot metal pieces for making hexagonal nut-blanks, driving two opposite wedge-shaped 20 forging members simultaneously into an endwise, movable hot metal bar at opposite longitudinal edges respectively of the bar and while the bar is at rest and thereby forming two opposite V-shaped recesses 25 which extend laterally through the bar and have their walls which face endwise of the bar in one direction forming two adjacent sides of a hexagonal piece to be produced and have their walls which face in the opposite direction forming two adjacent sides of 30 a hexagonal piece substantially completed by forming said recesses, and during the formation of said recesses exerting such pressure against the aforesaid edges from 35 said recesses in the last-mentioned direction as to thicken the bar and cause the bar to have its width between the pressure-receiving portions of said edges reduced in the direction of said recesses, then separating the 40 aforesaid wedge-shaped members the distance required to permit endwise movement of the bar in the first-mentioned direction, then feeding the bar endwise in said first-mentioned direction a predetermined distance, and then again driving said wedge- 45

shaped members simultaneously into the bar at the aforesaid point.

8. In the art of making hexagonal hot metal pieces for making hexagonal nut-blanks, producing a hot metal bar adapted to 50 be fed intermittently endwise in one direction and having a width measuring more than the diameter between diametrically opposite sides of said pieces and driving wedge-shaped forging members into said bar at its 55 longitudinal edges and at a predetermined point in relation to the path of the bar and while the bar is at rest and thereby forming two opposite V-shaped recesses which extend laterally through the bar and have their 60 forwardly facing walls forming two adjacent sides of a hexagonal piece to be produced and have their rearwardly facing walls forming two adjacent sides of a hexagonal piece completed by forming said recesses, and 65 while forming said recesses exerting such pressure against said edges rearwardly from said recesses a distance substantially equal to the distance between adjacent corners of the hexagonal product being formed as to 70 cause the bar to have its width between the pressure-receiving portions of said edges gradually decrease toward said recesses and measure at said recesses substantially the same as the aforesaid diameter, then separating the aforesaid wedge-shaped members, then feeding the bar forwardly endwise a distance substantially equal to one and one-half times the distance between adjacent corners of said product, and then 75 again driving said wedge-shaped members into the bar at the aforesaid point and thereby completing the formation of said product.

In testimony whereof, I sign the foregoing specification, in the presence of two witnesses.

JOSEPH A. COSTELLO.
